ATTY

UNITED STATES PATENT OFFICE.

MARTIN SMITH, OF CLEVELAND, OHIO.

DESIGN FOR A TOOL-HOLDING BLOCK.

SPECIFICATION forming part of Design No. 30,321, dated March 7, 1899.

Application filed February 9, 1899. Serial No. 705,123. Term of patent 7 years.

To all whom it may concern:

Be it known that I, MARTIN SMITH, a citizen of the United States, residing at Cleveland, in the county of Cuyahoga and State of Ohio, have invented and produced a new and original Design for Tool-Holding Blocks, of which the following is a specification, reference being had to the accompanying drawings, forming part thereof.

10 Figure 1 is a perspective front elevation, and Fig. 2 is a perspective rear elevation, of my new design in tool-holding blocks.

As shown in the drawings, the leading and material feature of my design consists in the 15 general outline and surface configuration of the block, the outlines being those of a rectangle having four equal side edges and a flat front surface relieved by a swell 2, running from edge to edge along one edge thereof and 20 deflected slightly along another edge at right angles thereto. This face view is further marked by a circular opening 3, and in a perspective view, as in Fig. 1, there is noticed

particularly an irregular recess or depression 4, which shows in the near edge 5, opposite the swell 2. A small opening 6 and a slight projection 7 likewise show in this view along the upper edge 8. In rear elevation, Fig. 2, a very different configuration appears, the irregular depression 4 coming here more fully 25 into view, as well as the opening 3, while the projection 7 stands out wholly disclosed at the edge of depression 4, as does also another but larger projection 9, beneath the opening 3. Otherwise this surface is flat and plain, and 30 a circular opening 10 relieves the otherwise plain near edge 12.

What I claim is—

The design for a tool-holding block, substantially as shown and described.

Witness my hand to the foregoing specification this 28th day of January, 1899.

MARTIN SMITH.

Witnesses:

H. T. FISHER,

R. B. MOSER.
